CLAIM

The ornamental design for the headlamp with band, as shown and described.

DESCRIPTION

FIG. 1 is an elevated isometric view of a headlamp and band showing the new design;

FIG. 2 is a front view of the headlamp and band as shown in FIG. 1;

FIG. 3 is a rear view of the headlamp and band as shown in FIG. 1;

FIG. 4 is a left side view of the headlamp and band as shown in FIG. 1;

FIG. 5 is a right side view of the headlamp and band as shown in FIG. 1;

FIG. 6 is a top view of the headlamp and band as shown in FIG. 1; and,

FIG. 7 is a bottom view of the headlamp and band as shown in FIG. 1.

In the drawings, the broken lines depict portions of the headlamp with band in which the design is embodied that form no part of the claimed design.

1 Claim, 5 Drawing Sheets
